DESIGN FOR A BLOWPIPE TIP

Everett P. Jones, Elizabeth, N. J., assignor to
Oxweld Acetylene Company, a corporation of
West Virginia

Application July 25, 1939, Serial No. 86,232

Term of patent 14 years

To all whom it may concern:

Be it known that I, Everett P. Jones, a citizen of the United States, residing at Elizabeth, in the county of Union and State of New Jersey, have invented a new, original, and ornamental Design for a Blowpipe Tip, of which the following is a specification, reference being had to the accompanying drawing, forming a part thereof, in which:

Fig. 1 is a view in side elevation of a blowpipe tip, showing the new design.

Fig. 2 is a view in front elevation;

Fig. 3 is a plan view of the end face of the tip; and

Fig. 4 is a bottom plan view of the tip.

The dominant feature of the new design resides

in the portion shown in full lines, in which a cylindrical rear end portion merges smoothly into an elongated forwardly extending tapered portion of circular cross-section. The elongated tapered portion is coaxial with the substantially cylindrical rear end portion and terminates in a front end portion which is reduced in transverse section and inclined with respect to the cylindrical and tapered portions. The inclined front end portion is quadrilateral in cross-section and an elongated protuberance is formed on the lower surface thereof to provide a shoe.

I claim:

The ornamental design for a blowpipe tip, substantially as shown and described.

EVERETT P. JONES.
